UNITED STATES PATENT OFFICE

2,481,633

GEAR-OPERATED WRENCH WITH SPIRAL DRIVE

William W. Wehner, Arlington, N. J., assignor of twenty-five per cent to Ernest A. Wehner, Arlington, N. J.

Application December 4, 1945, Serial No. 632,738

1 Claim. (Cl. 81—57)

1

This invention relates to wrenches, and more particularly to a wrench for use in tight or inconveniently accessible places.

An object of the invention is to provide a wrench which will turn a nut, bolt or other screw-threaded element in or out of work engagement without the necessity of sidewise movement of the handle of the tool, and which is equipped so as to be adaptable for threading pipes, for use as a screw driver, and for other similar rotational application.

The invention will be better understood by the following description with reference to the accompanying drawings, in which:

Figure 1 is a longitudinal cross section of a fragmentary portion of the tool handle;

Figure 1a is an elevation of a portion of the wrench end of the tool with one side of the housing removed;

Figure 2 is a cross-sectional view along the line 2—2 of Figure 1a;

Figure 3 is a side view, partly in section, of the ratchet elements;

Figure 4 is a top plan view of one of the ratchet collars;

Figure 5 is a top plan view of the other ratchet collar;

Figure 6 is a detail view of the ratchet pawl and the support therefor;

Figure 7 is a side view of a wrench adapter to fit into the basic socket of the wrench; and

Figure 8 is a front face view of the clutch selector button and associated keeper and guide plate therefor.

Referring now to the drawings, there is illustrated a work engager 10 (see Fig. 7) of a complementary external shape to fit into a polygonal opening 11' in an annularly toothed, rotary socket 11 and is, in effect, an adapter to function as a wrench, screw driver, pipe threader or whatever rotational work that is to be performed.

The annularly toothed socket 11 is rotated by means of a shaft 12 having a worm screw 13 formed integrally or attached thereon adjacent one end thereof.

The screw 13 is shown conventionally as of a plain straight form, but, in practice, the same may be, preferably, of the known form which is concave or curved arcuately from end to end thereof so as to increase its working strength and power because of greater spiral thread and tooth engagement between the screw 13 and the rotary socket 11. The shaft 12 is mounted rotatably in and extends longitudinally through an axial bore 14 in an elongated stem extension 14

2

of a handle having an apertured and laterally offset portion 15 to accommodate said socket 11.

At the opposite end of the shaft 12 is provided a polygonal portion 16 to which a suitable wrench can be applied so as to rotate the shaft. On one face of the polygonal portion 16 may be provided a conventional spring-protruded ball 17 to engage a recess in the socket of the applied wrench, as is customary in the application of such implements. So, too, a transverse hole 18 may be provided in the polygonal portion 16 for the insertion of a rod-like implement of small diameter to turn the shaft 12.

The just above described provisions are made to rotate the shaft by direct application of the said implements to in turn rotate the rotary member 11 which carries the adapter element 10.

An especial provision is made to cause rotation of the shaft 12 through the medium of a reciprocating element whose movement is longitudinally of the shaft by means and control of a selectively reversible ratchet driving mechanism as will now be described.

Sleeved about the shaft 12 and mounted in the bore of the tool handle so as to have both a rotatable and longitudinally reciprocatable movement is a sleeve element 19. This sleeve element 19 is of substantial length and it is provided at its outer end with a circular holding and manipulating handle 20 (see Fig. 1). This handle element 20, as illustrated, has its marginal portions rounded transversely and its hub portion is screw-threaded, as at 21, to the outer end of the sleeve 19. However, the handle element 20 may be of any other suitable type and attached in any other desirable manner to the sleeve 19 so as to be conveniently usable in both the rotation of the sleeve by said element 20 or by manipulation of the element in the reciprocation of the sleeve.

As shown, the shaft 12 is provided with a longitudinally extending circumferential lug 22 which rides in a longitudinal groove 23 provided in the sleeve 19. By this provision the shaft 12 and sleeve 19 are held against independent rotation, but are capable of longitudinal movement with relation to each other.

The sleeve 19 is provided on its outer face with a pair of oppositely formed spiral screw ways 24 which cross each other at each convolution thereof, the screw grooving of the tube producing a multiplicity of substantially diamond-shaped islands 25 in the conventional manner. Sleeved on the elongated sleeve 19 is a pair of ratchet collars 26 and 27, said collars being placed closely

adjacent each other (see Figs. 1 and 3) and they are supported in separated relation by an annular series of ball bearings 28, the collar 27 having thrust bearings 29 at its lower end and the other collar 26 having thrust bearings 30 at its upper end. The assembled collars 26 and 27 are held in place by a cap element 31 which is screwed onto the adjacent end portion of the stem extension 14 of the main body, said cap element having an internal collar 32 which abuts the upper set of ball bearings 30. By this provision and arrangement the ratchet collars 26 and 27 are held against endwise movement, but they are permitted rotatable movement either together or independently of each other, depending upon which pawl of the ratchet mechanism is set in working relation to the collar 26 or 27, as the case may be. That is to say, when the pawl elements of the ratchet mechanism are set in a neutral position, as will be later more fully described, both of said ratchet collars 26 and 27 are free to rotate freely in either direction with the sleeve 19, but when one of the pawl elements is set in working relation to its companion collar, that collar is held from rotation in one direction, while freely rotatable in the opposite direction, and the other collar is free to rotate in either direction, and vice versa.

Each of the collars 26 and 27 is provided on its interior face with a pair of diametrically opposed inclined and spirally arranged lugs 33, extending from end to end thereof and adapted to work in the screw grooves 24 on the exterior of the sleeve 19, the only difference being that the lugs 33 on the one collar are arranged in reverse order to the lugs on the other collar, that is to say, they are respectively arranged to cooperate with the right and left hand screw-threading of the sleeve 19. Each of the collars 26 and 27 is also provided with an annular series of ratchet teeth 34, the only difference being in the fact that the teeth of the one collar are in reverse order to those of the other collar and correspond to the right and left hand arrangement of the lugs 33, as the case may be.

Arranged in laterally opposed relation to the pair of ratchet collars 26 and 27 is an elongated rockable pawl-holding and controlling element 35 which is pivotally mounted, midway between its ends, on trunnions 36, said element 35 being located in a longitudinal recess 37 in the adjacent portion of the stem tool handle, and the trunnions 36 being journaled in suitable bearing openings provided therefor in the opposite side walls of the recess 37. A spring element 38 yieldably holds the rockable element 35 in a normally neutral position, and it also functions, together with a slidably mounted opposed button 39, which latter is adjusted in either direction from its neutral position to rock the element 35 and move one of its carried pawls 40 into working relation with respect to its companion collar 26 or 27, as the case may be.

As shown more clearly in Figures 3 and 8, the controlling button 39 for the rockable element 35 is held slidably in place by an escutcheon or keeper plate 41 which is placed to cover the elongated recess 37 and is secured in position by screw or bolt elements 42 which are insertible through apertures 43 provided therefor at the opposite ends of the plate 41 and into screw-threaded apertures provided obviously therefor in the adjacent portions of the stem extension 14 of the main body. As shown, the plate 41 is provided with a longitudinal slot 44 which com-

municates and extends on opposite sides of a central opening 45, with the outer ends of the slot 44 communicating with larger openings 46. The central opening 45 is in direct lateral alignment with the axis of the trunnions 36, while the outer openings 46 are in substantial central alignment with the pawls 40, that are carried by the element 35. So, too, the spring element 38 is of an elongated leaf type, the opposite end portions of which are semi-looped, as at 47, and are seated in the longitudinal groove or elongated recess 38' provided in the outer face of the element 35. By this provision, the spring element is held against lateral movement independently of the rockable element 35, but is permitted limited longitudinal movement in said grooved outer face portion of the element 35. Normally, this spring element 38 is moved somewhat outwardly from the outer face of the rockable element 35, but, in the neutral position of the element 35, with the controlling button 39 positioned so as to be engaged in the central opening 45 of the keeper plate 41, the middle portion of the spring element is thrust and deformed inwardly toward the adjacent middle portion of the rockable element 35. In this connection, it is noted that the button 39 is provided with a stepped portion 48 of transverse dimensions permitting it to slide freely in the slot 44 of the keeper plate 41. With this stepped portion 48 of the button positioned within the central opening 45 the spring element 38 holds the rockable member in its neutral position with both of the ratchet pawls out of engagement with their companion ratchet collars 26 and 27.

To set either of the carried pawls 40 on the rockable element 35 in working relation to its companion ratchet collar 26 or 27, as the case may be, the button 39 is moved toward either of the end openings 46 in the keeper plate 41 and when the button reaches the particular opening 46, the spring element 38 forces the adjacent end portion of the rockable element 35 toward the companion ratchet collar and places the carried companion pawl 40 in working relation to the teeth 34 of the particular collar. A like result follows when the button 39 is moved in the opposite direction. When the button 39 reaches either of the openings 46, the spring element 38 causes the button to seat a stepped portion 49 thereof of larger diameter than the stepped portion 48 into the particular opening 46, thus holding the button in its adjusted position until pressed inwardly against the tension of the spring element 38 so that it may be slid back to its normal central position. It is thus evident that the spring element 38 not only holds the rockable element 35 in its neutral and operated positions, but also holds the controlling button 39 in its neutral and adjusted positions.

As to the particular form of the rotary element 11 and the adapter element 10, it is here noted that the interior opening 11' of the rotary element 11 may be of any polygonal or other shape to receive the adapter element and hold the same against rotary movement independently of the rotary element. As shown (see Figs. 1a and 2) the rotary element has a generally circular opening 11', the wall of which is serrated or star-shaped. However, as just above noted, the shape of this opening may be of any other suitable or approved form. By the same token, the external contour of the adapter element 10 may be of other complementary shapes. In this connection, also, while not shown in detail, it is here noted that

the adapter element will have interior openings of various shapes to accommodate it to the particular kind of work intended; that is to say, for wrench purposes, the opening in the adapter element 10 will be either square, hexagonal or other complementary shape to engage the head of a bolt, screw or nut or other element to be likewise tightened or loosened. So, too, various forms of sockets may be provided in the adapter 10 to accommodate it to screw driver blades and the like, or, in other cases, it may be provided for the accommodation of pipe cutting, threading and other operations. As the particular form and arrangement of the accommodating opening in the adapter element is not concerned in the present invention, the same is not shown in detail in the accompanying drawings. However, the tool-accommodating opening in the adapter element 10 is indicated only schematically, as at 10' in Figure 7.

In some adaptations of the invention, the opening 11' in the socket 11 may be provided at one or more places with a spring-urged ball or balls 50, said ball elements to engage in complementary recesses 51 placed correspondingly on the outer face of the adapter element 10. So, too, the mounting of the rotary element 11 in the offset end portion 15 of the main body may be accomplished in any approved manner. As shown, however, the main body is divided longitudinally so that the offset end portion produces two opposed hollow housings 52 in the top and bottom walls of which are provided aligned openings 53 through which the opposite end portions of the rotary element 11 protrude, the intermediate peripherally toothed portion 54 of the rotary element being in the form of an integral annular collar, which, at opposite sides, abuts the adjacent inner faces of the upper and lower walls of the sections 52 (see Fig. 2). The chamber within the housing sections 52 also affords a container for a heavy oil or semi-plastic lubricant.

As to the pawl elements 40 of the ratchet mechanism, it is here noted that the same may be of any suitable or approved form and arrangement. A practical and efficient form of the ratchet pawls and the arrangement thereof is illustrated in detail in Figure 6, in which figure the showing is a fragmentary cross-section through the rocker element 35 in the region of the ratchet collar 27. As shown, the rockable element 35 is of a peculiar undercut form in cross-section. Its peculiar form produces a perpendicular shoulder 55 at one longitudinal edge thereof, against which shoulder 55 the pawl element 40 normally abuts. As illustrated more clearly in Figure 3, the pawl element is in the form of a substantially wide plate, and as shown in Figure 6, it is provided at one edge with a bead 56 which is circular in cross-section and is fitted into a corresponding opening 57 in the body of the element 35 adjacent the base of the perpendicular flange or shoulder 55. The pawl 40 is yieldably held against said shoulder 55 by a spring element 58 which is supported on an arcuate stem 59 protruding from the face of the pawl and the stem and spring being both received in a correspondingly arcuate recess 60 in the opposed body portion of the element 35. By this provision, when an attempt is made to rotate the ratchet collar 27 in one direction, the pawl 40, being against the shoulder or flange 55, arrests the movement of the collar, but, when the collar is rotated in the opposite direction, the spring 58 yields and permits the pawl to swing away from the shoulder or flange 55.

55 so that there is an escapement of the teeth 34 from the previously engaged pawl 40. The same construction and pawl arrangement obtains as to the other ratchet collar 26, except that the relative positions of the flange or shoulder 55 and the pawl 40 is in reverse order to that shown in Figure 6.

The operation of the tool of the present invention may be accomplished in different ways. One method is to rotate the shaft 12 by direct application of a wrench or other implement to the protruded end of the shaft, thus directly rotating the worm screw 13 and driving the rotatable element 11. This, of course, may be accomplished by rotating the shaft 12 in either direction, as desired or necessary. Another method of operation is to grasp the manipulating head or element 20 at the outer end of the sleeve 19 and rotate the same, thus turning the sleeve, and, through the engagement of the lug 22 on the shaft 12 in the groove 23 of the sleeve 19, the shaft 12 is thereby positively rotated in either direction. It is here also noted that, in the direct rotation of the shaft 12 by the rotation of the sleeve 19, as just described, the lug and groove engagement between the shaft and the sleeve is such that the sleeve may be withdrawn to different distances outwardly on the shaft, as may be desired for convenience, and with the sleeve thus adjusted, the same may be rotated by means of the manipulating head 20 at the outer end thereof. It is, of course, understood that to rotate the shaft 12 by means of the sleeve 19, as just previously described, the rockable element 35 must be set in a neutral position so that neither of the pawl elements 40 is in working relation to the respective ratchet collars 26 and 27. Still another method of operation is by reciprocating the sleeve 19 longitudinally, and for which operation either one of the pawls 40, according to the direction in which it is intended to rotate the shaft 12, is set in working relation to its companion collar 26 or 27, as the case may be. Thus, with one of the ratchet collars estopped from 45 rotation in one direction by the setting of the companion pawl 40, if the sleeve is forced longitudinally in one direction, the collar being held by the pawl, the sleeve and the shaft 12 keyed thereto are turned in the direction according to 50 the threading of the collar, that is, as to whether it is right or left hand, but on the return stroke of reciprocation, the collar is free to rotate, hence, the movement of the keyed shaft and sleeve is longitudinal and without rotation. By the same token, which the other pawl element 40 placed in 55 working relation to its companion ratchet collar, the combined rotation of the shaft and sleeve is positive in one direction of reciprocation, but in an opposite direction of rotation.

60 While the accompanying drawings illustrate a practical exemplification of the invention, it is understood that modifications in the same is contemplated within the spirit and scope of the appended claim. The invention, therefore, is not limited to the specific construction and arrangement shown.

Having thus described the invention, what is claimed is:

70 A manually operated rotatable tool comprising a tool handle having a longitudinal bore therethrough and an apertured offset at one end thereof, a rotatable socket journaled in said offset and having peripheral gear teeth thereon, a rotatable shaft in the bore of said handle having a polygonal outer end portion disposed beyond the end

of said handle remote from said offset, a worm gear on the inner end of said shaft meshing with the gear teeth on said socket, and manually operated means for rotating said shaft comprising a sleeve surrounding said shaft within said handle bore and having a longitudinal keyway in the inner surface and a pair of oppositely curved spiral grooves in the outer surface thereof, a lug on said shaft engaged in said sleeve keyway rotationally connecting said sleeve to said shaft while providing freedom of relative longitudinal movement therebetween, a pair of juxtaposed collars journaled in said handle surrounding said sleeve having internally thereof respective spiral lugs oppositely curved and engaged respectively in said oppositely curved sleeve grooves, and external ratchet teeth on said collars, the ratchet teeth on said two collars facing in opposite directions.

5 tions, and pawl means carried by said handle selectively engageable with said collars to control the direction of rotation of said sleeve upon lengthwise movement thereof relative to said shaft and said handle.

WILLIAM W. WEHNER.
